ATTORNEY

UNITED STATES PATENT OFFICE.

CHARLES JULIUS BRUSCHKE, OF LAKE VIEW, ILLINOIS.

DESIGN FOR A CHAIR.

SPECIFICATION forming part of Design No. 14,975, dated April 29, 1884.

Application filed August 27, 1883. Term of patent 7 years.

To all whom it may concern:

Be it known that I, CHARLES J. BRUSCHKE, a citizen of the United States of America, residing at Lake View, in the county of Cook

5 and State of Illinois, have invented and produced a new and original Design for Chairs, &c., of which the following is a specification, reference being had therein to the accompanying drawings.

10 My design relates to chairs, sofas, and like articles of furniture.

In the drawings forming part hereof, Figure 1 is a front view, and Fig. 2 a side view, of a chair constructed in accordance with my design.

15 In the drawings, A represents the seat of a chair, which is in form similar to the body of a small boat. This seat is supported on legs B, which I make in the form of oars, as shown.

20 The end pieces and supports for legs B are shaped to represent anchors, as shown at C. The back D of the chair I construct to represent the sail of a boat, and the arms may be formed of suitable ropes and cross-bars to carry 25 out the representation. The seat A and back

D may be upholstered in any desirable manner. It will be apparent that the design may be applied to chairs, sofas, or other articles of furniture.

What I claim is--

1. The within-described design for chairs, which consists of a seat having the form of a boat, a back in the form of a sail, as described and shown.

2. The within-described design for chairs, 35 which consists of a seat having the form of a boat, a back in the form of a sail, and legs in the form of oars, as described and shown.

3. The within-described design for chairs, which consists of a seat having the form of a 40 boat, a back in the form of a sail, legs in the form of oars, and supports to said legs in the form of an anchor, as described and shown.

In testimony whereof I affix my signature in presence of two witnesses.

CHARLES JULIUS BRUSCHKE.
